CONTAINER

Filed June 19, 1928

UNITED STATES PATENT OFFICE

HENRY KIELBERG, OF MARTINS FERRY, OHIO, ASSIGNOR TO WHEELING STEEL CORPORATION, OF WHEELING, WEST VIRGINIA, A CORPORATION OF DELAWARE

CONTAINER

Application filed June 19, 1928. Serial No. 286,622.

This invention relates broadly to sheet metal containers, and more specifically to a can or pail and means for attaching a head or cover thereto.

5 The primary object of the invention is to provide a can or pail of the character commonly employed as containers for paints and other liquids or semi-liquids, having a removable cover and associated novel and im-
10 proved means whereby said cover may be secured in closing relation to the container.

A further object is to provide a cover for cans and pails having associated therewith a sealing ring whereby it may be rigidly se-
15 cured in place and which may be bodily re-
moved with a minimum of effort and without
injury to or bending of any part of the cover,
thus adapting said cover for frequent re-use.

A still further object is to provide a sealing
20 ring which may be sprung or pressed upon
the cover in self-retaining relation to the
latter by the manufacturer, thus to adapt said
ring and cover for shipment and for applica-
25 tion by the packer to the containers as if made
in a single piece.

Another object is to provide a sealing ring
having improved means whereby its ends
may be attached, one to the other.

In describing the invention in detail, ref-
30 erence is herein had to the accompanying
drawings, in which—

Figure 1 is a perspective view of the seal-
ing ring;

Figure 2 is a view partly in side elevation
35 and partly in section showing a can or pail
equipped with the invention and illustrating
the application of the latter.

Figure 3 is an enlarged detail view in side
elevation of the two ends of a preferred form
40 of sealing ring as they appear prior to at-
tachment of one end to the other;

Figure 4 is a similar view showing the two
ends in attached relation;

Figures 5 and 6 are views similar to Figs.
45 3 and 4, respectively, showing a modified
form of attaching means for the ring ends;

Figures 7 and 8 are views similar to Figs.
3 and 4, respectively, showing a second modi-
fied form of end attaching means; and

50 Figures 9 and 10 are views similar to Figs.

3 and 4, respectively showing a third modi-
fied form of end attaching means.

Referring to said drawings, 1 designates a
can or pail having at its upper end an out-
wardly turned bead or roll 2. Seated in over-
lying relation to said roll is an outwardly di-
rected rim 3, approximately semi-circular in
cross section, formed circumferentially on a
cover or closure 4 for the container.

55 Mounted in closely seated embracing rela-
tion to the rim 3 of said cover is the body
portion of a ring 5, arcuate in cross section,
formed of a single length or strip of sheet
metal and which has a plurality of integ-
60 ral relatively spaced lugs 6 depending from
its lower edge.

65 Said ring is designed to be pressed or
sprung upon the rim 3 of the cover, in such
manner that it is self retained with respect
to the cover, prior to application of the cover
70 to the container, or prior to shipment to the
packer by whom the covers are applied. The
cover and the ring are applied, as if made in
one piece, by the packer for closing the con-
tainer, the lugs 6 being bent into underlying
75 seated relation to the roll 2 for securing said
applied parts in place.

The ends of the sealing ring, as shown in
Figs. 1 to 6, 8 and 9 are designed to be dis-
posed in overlapping attached relation. As so
shown in Figs. 1 to 4, the overlapping end is
provided with a suitably located transverse
slot 7 which is adapted to have projected out-
wardly therethrough a tongue 8 which is
struck up from the metal of the overlapped
85 end of the ring and which extends longi-
tudinally of and parallel to the ring and in a
direction away from said end. A shallow in-
wardly depressed seat 9 substantially corre-
sponding in size and form with said tongue
90 is provided in said overlapping end of the
ring for the reception of said tongue, where-
by the latter is permitted to occupy substan-
tially the plane of the peripheral surface of
said ring.

95 In the modification shown in Figs. 5 and
6, the tongue 8^a is formed by a turned back
extension of the overlapped end of the ring.
Additionally, a second transverse slot 10
parallel to the slot 7^a is provided between the
100

latter and the terminal edge of the overlapping end. A depressed seat 9^a for the tongue 8^a extends from one of said slots to the other, thus to permit the point of said tongue to be returned through the slot 10, as shown in Fig. 6.

The modification shown in Figs. 7 and 8 comprises tongues 8^b, similar to the tongue 8 in Figs. 1 to 4, formed in each of the ends of the ring. Said tongues are designed to engage in slots 7^b provided in the adjacent ends of an overlapping coupling member 11 of short length, each of said slots having associated therewith tongue seats 9^b similar to the seats 9 of Figs. 3 and 4.

In the modification shown in Figs. 9 and 10, the overlapped end is provided with an H-slot 7^c defining oppositely disposed transverse tongues 12. The overlapping end has a semi-cylindrical head 13 joined to the body of the ring by a neck 14 of reduced width. Said head 13 is designed to seat in the opening formed by outward bending of said tongues 12 and then to have said tongues turned back in overlying seated relation thereto, as shown in Fig. 10. A short longitudinal extension or tongue 15 integral with the head 13 is designed to overlie the ring rearward of the H-slot 7^c, as shown in Fig. 10.

Following attachment of the two ends of the ring 5 in the manner shown in Fig. 4, the seat 9 and the therewith engaged tongue 8 are together subjected to the action of a punch press in which a concavo-convex button or knob 16 is pressed in said parts, thus to safeguard against chance relative disengagement of said ends. Similar buttons or knobs 16^b and 16^c are pressed in interengaged members or parts, as shown in Figs. 8 and 9, respectively.

To remove the ring shown in Figs. 1 to 4, the tongue 8 is pried outwardly by means of a suitable instrument to the extent that the overlapping end is released, whereupon said ring may readily be stripped from the container by pulling upon said end. Similarly, when the tongue 8^a of Figs. 5 and 6, one or the other of the tongues 8^b of Figs. 7 and 8, and the tongues 12 of Figs. 9 and 10, are bent outwardly, separation of the attached ends of the rings 5 may readily be effected to permit stripping of the latter from cover sealing position.

What is claimed is—

- 55 1. A sealing ring of the character described, comprising a single strip of sheet metal, one end of said ring having therein a transverse slot and an inwardly pressed seat extending from said slot toward the terminal edge of said end, and the other end of said ring having a struck-up tongue entered outwardly through said slot and engaged in said seat so as to lie substantially flush with the first named end of the ring.
- 60 2. A sealing ring of the character de-

scribed, comprising a single strip of sheet metal, one end of said ring having therein a transverse slot and an inwardly pressed seat extending from said slot toward the terminal edge of said end, and the other end of said ring having a struck-up tongue entered outwardly through said slot and resting upon said seat, said tongue and said seat each having therein an outwardly pressed concavo-convex button and said buttons being disposed in interengaged relation.

3. A sealing ring of the character described, comprising a strip of sheet metal having a longitudinally disposed tongue formed on one end thereof and received in and having its sides engaged by the end walls of an opening in its opposite end, the free end of the tongue facing inwardly of the ring, and the tongue being wholly disposed exteriorly of and seated throughout its length against the outer face of the portion of the ring underlying the tongue, and said tongue and the portion of the ring which underlies said tongue having therein outwardly pressed buttons occupying interengaged relation.

4. A sealing ring of the character described, comprising a strip of sheet metal having means whereby its ends are joined, said means including a tongue formed on one of the ends of said ring and an opening in the portion to which said end attaches, said tongue being projected through said opening and the free end of the tongue facing inwardly of the ring and the tongue being wholly disposed exteriorly of and seated throughout its length against the outer face of the portion of the ring underlying the tongue, and having its sides engaged with the end walls of the opening, said tongue and said portion having formed therein concavo-convex buttons which are interengaged one with the other.

5. A sealing ring of the character described, comprising a strip of sheet metal, one end of said ring having therein a transverse slot and an inwardly pressed seat extending from said slot toward the terminal edge of said end, and the other end of said ring having a struck-up tongue entered outwardly through said slot and engaged in said seat, so as to lie substantially flush with the outer first named end of the ring, and means to hold the tongue in its seat and with its outer end flush in the seat.

In testimony whereof, I affix my signature.

HENRY KIELBERG.
